United States Patent Office

Des. 186,452
Patented Oct. 27, 1959

186,452

FIGURE TOY

Willis M. Lakin, Chicago, Ill., assignor to Marlin Toy Products, Inc., Chicago, Ill., a corporation of Illinois

Application August 18, 1958, Serial No. 52,241

Term of patent 14 years

(Cl. D34—15)

Fig. 1.

Fig. 2.

Fig. 1 is a front elevational view of a figure toy showing my new design; and

Fig. 2 is another front elevational view of the article of Fig. 1 with the hat in an alternate position.

The figure toy is symmetrical and the rear is substantially plain.

I claim:

The ornamental design for a figure toy, as shown and described.
